UNLOADING NET FOR EXTRACTORS

Archie O. Long, Kansas City, Mo.

Application March 17, 1932. Serial No. 599,484

3 Claims. (Cl. 210—76)

My invention relates to extractors and more particularly to loading and unloading nets for extractors.

Nets of this character have been made of a circular series of cords provided with rings on their lower ends for receiving a draw-cord to gather the ends together, but have been found to be impractical because the cords were not sufficiently durable, and for the reason that the net 10 would not completely unload when the draw cord was released.

Other nets have been constructed of canvas, duck, or similar material formed into a bag by drawing the lower circumferential edge together 15 with a draw string. The latter type of net proved unsatisfactory for the reason that the passage of water from the articles in the bag was hindered by the relatively closely woven material.

The principal objects of my invention are, 20 therefore, to provide a durable open net that will positively unload upon release of the draw cord and wherein the draw cord can be easily and quickly threaded for forming a substantially closed lower end for the net.

25 Another object of my invention is to provide improved means for securing the ends of the draw-cords together.

In accomplishing these and other objects of my invention, I have provided improved details of 30 structure, the preferred form of which is illustrated in the accompanying drawings, wherein:

Fig. 1 is a perspective view of a loaded net, embodying my invention, being elevated from an extractor.

35 Fig. 2 is an elevational view of the net in unloaded condition.

Fig. 3 is a fragmentary sectional view, showing a preferred form of latch for locking the net to the extractor housing.

40 Fig. 4 is a detail perspective view of my improved connector for securing the ends of a draw cord together.

Referring more in detail to the drawings:

1 represents an extractor housing of cylindrical 45 form adapted to contain the usual perforated basket 2, and a concentric bearing housing 3 projecting upwardly into the housing encloses a suitable bearing whereon the basket is rotated.

The upper end of the extractor housing terminates in an inwardly inclined flange 4 for supporting the usual cover (not shown) and a cover ring 5, of an unloading net later to be described, is provided with a plurality of notches 6 adapted to register with corresponding plates 7 fixed, as 55 indicated at 8, to the upper end of the extractor

for insuring rotation of the ring with the extractor housing.

In order to anchor the cover ring to the extractor, a latch mechanism is provided including 60 socket members 9 secured, as by welding, to the lower face of the ring member for receiving latch bolts 10, urged radially from each socket by an expansion spring 11 having opposite ends bearing respectively on an end wall 12 of the socket and against the inner end of the latch bolt. The 65 outer end of each bolt is extended through an aligned notch 13 of a depending annular flange 14 of the cover ring and an upstanding boss 15 of the bolt projects through a registering slot 16 of the ring and is provided with an opening 17 70 for receiving the outer end of a link member 18. A cross bar 19 formed on a ring 20 connecting the inner ends of the links is adapted to engage the hook 21 of an elevator (not shown) commonly provided for lifting a loaded net from an extractor 75 housing.

The mechanism thus far described does not constitute a part of my present invention, but has been disclosed for the purpose of clarifying the relation thereto of a net 22 associated therewith 80 and now to be described in detail.

Fixed in spaced relation to the inner face of the depending flange 14 by bolts 23, or the like, is an annular band 24, and secured in the space between the band and flange on the bolts 23 are 85 chains 25 preferably formed of non-corrosive material.

As will be particularly clear from Figs. 1 and 2 of the drawings, the chains depend from the cover ring in an annular series and are held in 90 parallel relation throughout a portion of their length by connecting links 26. While selected strings of chains continue perpendicularly downwardly from the connecting links and terminate in rings 27, adjacent strings converge inwardly 95 from the connecting links and are connected in pairs to opposite sides of the main strings as indicated at 28, 29 and 30, thereby defining triangular segments adapted when gathered at their lower ends, to form a substantially semispherical 100 pocket for retaining articles of laundry in the net.

In order to draw the lower ends of the segmental portions together, a flexible cable 31 is provided for threading through the rings 27 and 105 a ring or loop 32, of sufficiently large dimensions to prevent passage thereof through the rings, is connected to one end of the cable.

On its opposite end, the cable is provided with a shaft portion 33 having an elongated opening 110

34 for receiving a wedge 35 preferably retained in engagement with the shaft by a resilient blade 36, the blade having its lower end secured either to the wedge or in the opening 34 of the shaft. 5 The wedge is provided with an opening 37 for receiving the eye member 38 of a pull cord 39.

Assuming a net to be constructed and secured to the cover ring of an extractor, the procedure of loading and unloading the net would be as follows.

When the net is supported in elevated position on the hook 21, the draw cable is threaded through the rings of the triangular segments and the ends of the cable are connected, in the manner clearly shown in Fig. 4. It is to be noted that, when in connected condition, the cable forms a constricted lower ring of sufficient diameter to pass freely over the bearing housing and it is important that the net be properly aligned with the bearing housing when lowering the net into the extractor. 10 After the lower ends of the net have been drawn together and the net is lowered into the perforated extractor cylinder, thereby engaging the latch bolts with their respective notches, the net is loaded with wet laundry and moisture is drawn therefrom by centrifugal force, in the usual manner.

The ring 20 of the cover member is then connected to the elevator hook and as the cover ring is drawn upwardly, the latch bolts are withdrawn from the corresponding notches in the extractor rim and the net is elevated from the extractor. 15 A jerk on the cord 39 then withdraws the wedge from the slot of the shaft 33 and the triangularly shaped segments drop to the position shown in Fig. 2, thereby quickly and entirely unloading

the laundry from the net onto a suitable support.

The draw cable may then be again threaded through the rings of the segments for repeating the loading process.

What I claim and desire to secure by Letters Patent is:

1. A device of the character described including an upper anchor member, a circular series of vertical flexible members depending from said anchor member, the lower ends of some of said flexible members being connected to other of the vertical members to produce a plurality of triangular segments adapted to form a substantially semispherical lower end when gathered, and means for maintaining said segments in gathered condition. 80

2. A device of the character described including an upper anchor member, a circular series of vertical chains depending from said member, links in spaced relation with said member for connecting the chains in parallel relation, some of said chains being connected to other of the vertical chains to produce a plurality of triangular segments adapted to form a substantially semi-circular bag when drawn together, and means for drawing said segments together. 85

3. A device of the character described including an upper support, a circular series of flexible members depending from the support and terminating in rings, a draw cord adapted to be passed through said rings having a loop on one end, a shaft on the opposite end of the cord for projection through the loop, and retractable means associated with the shaft for preventing withdrawal of the shaft from said loop. 90
